UNITED STATES PATENT OFFICE

173,244

GAME BOARD

Eric G. Shalkhauser, Washington, Ill.

Application February 10, 1954, Serial No. 28,955

Term of patent 14 years

(Cl. D34—5)

To all whom it may concern:

Be it known that I, Eric G. Shalkhauser, a citizen of the United States, residing in Washington, in the county of Tazewell and State of Illinois, have invented a new, original, and ornamental Design for a Game Board, of which the following is a specification, reference being had to the accompanying drawing, forming a part hereof.

The figure is a plan view of the game board showing my new design.

The game board is of conventional thickness, and shaded to illustrate contrasting colors.

I claim:

The ornamental design for a game board as shown and described.
